UNITED STATES PATENT OFFICE.

EDWIN H. MARTIN, OF CLEVELAND, OHIO.

PUMPING-ENGINE.

SPECIFICATION forming part of Letters Patent No. 279,407, dated June 12, 1883.

Application filed April 19, 1883. (No model.)

To all whom it may concern:

Be it known that I, EDWIN H. MARTIN, a citizen of the United States, residing at Cleveland, county of Cuyahoga, and State of Ohio, have invented certain new and useful Improvements in Pumping-Engines; and I do hereby declare the following to be a full, clear, and exact description of the invention, such as will enable others skilled in the art to which it applies to make and use the same, reference being had to the accompanying drawings, forming part of this specification.

This invention relates to certain improvements on the construction of my pumping-engine, set forth in United States Letters Patent No. 223,000, December 30, 1879. These improvements pertain, respectively, to the lessening of initial cost of the engine; to the economizing of area necessary as engine-room, and to the saving of labor in the care of the engine. The construction resulting in such advantages becomes of peculiar significance when it is remembered that this class of machinery is of necessity heavy in its parts and extensive in its proportions. In making these improvements the controlling aim has been to so build the engine that certain forms of the previously-patented construction may be dispensed with and be substituted by more practicable forms; also, that the superficial area of the engine may be made small, and thus permit of its location and accommodation in less-sized quarters than heretofore; and, finally, to form the main component parts of the engine in such juxtaposition as to adapt them to be more readily observed and attended to than in the old engine.

With these several ends in view the invention consists in constructing two steam-cylinders respectively over two water-cylinders, and adapting the connecting parts of the different cylinders so that they may operate to advantage in such combination.

Referring to the drawings, Figure 1 is a view in longitudinal vertical section on center line of one of the two pairs of steam and water cylinders employed in the invention. Fig. 2 is a top view of the invention, one steam-cylinder and connecting parts being removed in order to show the water-cylinder and connecting parts otherwise concealed.

There are two steam-cylinders, each having

its operative parts independent of the other, but both of them being connected to the same driving-shaft, A. There are also two water-cylinders, each having its operative parts independent of the other, but both of them being connected to one shaft, B, the latter shaft being located below and to the rear of shaft A. Both shafts are located transversely on the bed C of the engine, the steam and water cylinders being formed longitudinally on said engine-bed. Each water-cylinder has a steam-cylinder formed directly upon it in longitudinal vertical plane therewith. The driving-shaft A has a crank, a, formed on each end thereof, the two cranks being at right angles to each other. Said shaft carries a fly-wheel, D, and a pinion, E. This pinion gears into a spur-wheel, F, mounted on shaft B, the latter shaft having a crank, b, on each end thereof. These two cranks are also at right angles to each other. Each steam-cylinder G has its piston-rod H connected by a pitman, L, to its appropriate crank a. Each water-cylinder M has its piston-rod N connected by a pitman, P, to its appropriate crank b. By suitably operating the steam-cylinders the thrusts of both shafts A and B is downward, and thereby tending to steady the motion. Each steam-cylinder is provided with a main valve, c, and a cut-off valve, d, both said valves being rotary and driven by eccentrics on the driving-shaft. The main valve-rod e connects directly with its eccentric f on said driving-shaft. The cut-off valve-rod g is connected directly to rock-shaft R, and the latter connects by rod h to eccentric l of the driving-shaft. An adjusting device, S, permits of any desired adjustment of the cut-off, as the operation may be wished to be made more or less quick. The pump-valves m are simple blocks of wood, controlling ample and direct water-passages. They are provided on the top and sides with a thin casing of metal to give them weight and also to prevent wearing in the guides between which they work.

Should any slight repairs or packing be required in any one of the different independent sets of steam or water parts, said set may be disconnected from the other sets, and such repairs or packing be accomplished without stopping the water supply.

Having fully described the invention, what

I claim as new, and desire to secure by Letters Patent, is—

1. In a double pumping-engine, the combination, with the two water-cylinders M and the two steam-cylinders G, said four cylinders formed in the forward portion of the engine-bed C, of the two transverse shafts A and B, respectively having bearing in the rear portion of said engine-bed, and connecting parts extending forward from shaft B to the water-cylinders and from shaft A to the steam-cylinders, substantially as and for the purpose set forth.
2. In a double pumping-engine, the combination, with the two steam-cylinders G, each having an independent set of operating parts connected to the pinion-shaft A, of the two water-cylinders M, each having an independent

set of operating parts connected to the spur-wheel shaft B, said steam-cylinders being respectively formed longitudinally on the water-cylinders, substantially as and for the purpose set forth.

20

3. In a double pumping-engine, the combination, with the two steam-cylinders G, each connected to the pinion-shaft A, of the two water-cylinders M, each connected to the spur-wheel shaft B, having its bearing below and to the rear of said pinion-shaft, the steam-cylinders being formed one on each water-cylinder, substantially as and for the purpose set forth.
